UNITED STATES PATENT OFFICE

2,229,989

CLIP MEMBER AND CLIP MEMBER
INSTALLATIONSWilliam G. Roby, Park Ridge, Ill., assignor to
Cinch Manufacturing Corporation, Chicago,
Ill., a corporation of Illinois

Application April 6, 1937, Serial No. 135,277

2 Claims. (Cl. 200—134)

This invention relates to clip devices for retaining electrical articles such as a fuse member and to installations of the same.

One object of my invention is to provide a clip device having an article-retaining portion and a wire-receiving terminal formed as one piece so that there may be no voltage loss between the wire-receiving terminal and an article to be retained by the clip device, the aforesaid voltage loss being a common fault of clip devices now known in the art in which the wire-receiving terminal is a separate piece with the article-retaining portion of the device.

A further object of my invention is to provide attaching portions as an integral part of the clip device providing a means for securing the device to a supporting part.

Other objects of my invention will be apparent from inspection of the drawing and the specification hereinbelow set forth.

Referring to the drawing, in which I have illustrated a preferred form of my invention:

Figure 1 is a top plan view of a pair of my improved clip devices secured to a supporting part 5 and carrying between them a fuse member;

Fig. 2 is a front view of the installation shown in Fig. 1;

Fig. 3 is a section taken along the line 3—3 of Fig. 2;

Fig. 4 is an end view of the installation shown in Figs. 1 and 2;

Fig. 5 is a bottom plan view of the installation shown in Figs. 1—4;

Fig. 6 is an end view of my improved clip device per se; and

Fig. 7 is a front view of the clip device shown in Fig. 6.

A preferred form of my installation, as shown in Figs. 1—5, provides a supporting part 1, preferably made of insulating material, carrying a pair of spaced fuse clips 2—2. The clip devices 2—2 are secured to the support 1 by integral attaching means extending through apertures 3—3 in the supporting part and engaging the material of the support adjacent the apertures. Opposed ends of a fuse member 4 are received by resilient arms of the clip device 2—2 and maintained in assembly therewith.

Referring to my improved clip device, I have shown one which, in my preferred form, is made from one piece of sheet metal material. My clip device has a base portion 5 and upstanding spaced resilient arms 6—6 extending from opposed sides of the base 5 and providing an opening for receiving an opposed end of the fuse mem-

ber 4. The arms 6—6 of the clip device are of bowed construction, in my preferred form, whereby they may expand and contract to hold the fuse member in place, and, at the same time, enable the fuse member to be readily removed or replaced. A wire-receiving terminal 7 extends from an edge of the base 5 between the resilient arms 6—6, in my preferred form, in a direction relative to the base, which is substantially opposite to that taken by the arms 6—6. An aperture 10 (Fig. 6) may be provided near an end of the terminal 7 whereby a wire (not shown) may be soldered to the terminal. As a means for attaching my clip device to a supporting part, I have provided lug portions 8—8 which are formed entirely from material of the respective arms 6—6 and which extend from the base 5 in substantially the direction taken by the terminal 7 (Fig. 7). The apertures 9—9 in the arms (Fig. 7), which are provided through taking material from the arms to form the lugs 8—8, performs a useful function in that they serve to increase the resiliency of the arms.

Assembly of my clip device with a supporting part is a relatively simple matter and is carried out through moving the clip device toward the support so that the base 5 abuts the support with the wire-receiving terminal 7 extending through an aperture 10 of the support and the lug portions 8 extending through the apertures 3 to a position beneath the support. The lug portions 8 are now struck by a suitable tool to bend them into clamping engagement with the material of the support adjacent the apertures 3 (Fig. 3) whereby the clip device is securely fastened to the support.

As a result of my invention I have provided a one-piece clip device which is an improvement over clip devices of several parts which are now in common use through reason of the fact that it is relatively less expensive to manufacture and attach. Also, my device represents improvements over those clip devices in which a rivet or similar means is used to secure the same to a supporting part as it is impossible to distort the article-retaining portions of my clip in mounting the same upon a support in the manner in which similar portions of those devices using a rivet are distorted during attachment of the last-mentioned devices to a support.

Although I have illustrated and described a preferred form of my invention, I do not wish to be limited thereby because the scope of my invention is best set forth in the following claims.

I claim:

50

55

1. A fuse clip device having a base portion and laterally spaced resilient arm portions extending from said base, said arms having portions adapted to receive and engage a portion of an electrical part, at least one lug portion integral with said clip portion and formed at least partly from material taken from within an arm portion, said lug portion adapted to extend into an aperture of a supporting part and engage material of said part adjacent said aperture, and wire-receiving means in electrical contact with said clip device.

2. A fuse clip device having a base portion and laterally spaced resilient arm portions extending from said base, said arms having portions adapted to receive and engage a portion of an electrical part, integral lug portions extending from said base in a direction substantially opposite to that taken by said arms, said lugs being formed from material entirely within said resilient arms, and wire-receiving means in electrical contact with said clip device.
